UNITED STATES PATENT OFFICE.

EDWARD C. DOUGLAS, OF CHICAGO, ILLINOIS.

REVOLVING CARD-HOLDING STAND.

No. 911,385.

Specification of Letters Patent.

Patented Feb. 2, 1909.

Application filed June 17, 1907. Serial No. 379,364.

To all whom it may concern:

Be it known that I, EDWARD C. DOUGLAS, a citizen of the United States, residing in Chicago, Cook county, Illinois, have invented certain new and useful Improvements in Revolving Card-Holding Stands, of which the following is a full and correct specification, reference being had to the accompanying drawings, forming a part there-
10 of, and in which—

Figure 1 shows my said device in elevation, a fragment of one element broken away to show the construction behind it. Fig. 2 shows in plan view the central part shown 15 in Fig. 1 without the top shelf-members *h* and parts *c* and *e*; Fig. 3 shows the connecting-bars *j* in side view. Fig. 3^a shows Fig. 3 in end view, and Fig. 4 shows the same in plan view, looking into its U-shaped chan-
20 nel. Fig. 5 shows, in end view, the construction of all shelves intermediate the end shelves. Fig. 6 shows Fig. 5 in side view, and Fig. 7 shows the same in top plan view.

Like reference letters denote like parts
25 throughout.

The object of my invention is to produce a card-stand for holding fancy postal cards, and like articles, for both the use of stores and private homes and any place where such 30 cards are stored, which shall be so convenient and at the same time so cheap that it may be within the reach of all who can make use of it.

To attain said desirable ends I construct 35 my said device in substantially the following manner, namely: I provide a base *a* pro-
vided with a central boss *a'* from the center of which rises an iron rod or stem *b* threaded and provided with a nut *c*. Around said 40 stem are placed four identically alike chan-
neled uprights, each formed of a back *f* and two flanges *g* having a series of slots *f'*. The slots are spaced apart according to the size of the goods the said shelves are to hold.
45 Said shelves consist of two bottoms *h* which are connected by central double walls *i*' connected by an arch *h'*, and outer walls *i*, all integral with the part *h*, and into the front or outer ends of said arch is cut a slot *o* into
50 which is received the U-shaped channel-bar *j* provided with bosses or projections *k* integral therewith, as clearly shown in Figs.

3 and 4. Said bosses are placed under the shelf-bottoms *h* to sustain their outer ends.

All shelves intermediate the end shelves 55 are connected at their outer edges by means of a lip *l* forming an integral part of all the upper parts of all intermediate shelves. Said lips *l* are turned down and folded over the edges of the under part of such shelves 60 to form a clamp *m* which unites the said front edges of said shelf parts firmly, neatly, and permanently, as clearly shown in Figs. 6 and 7, the part *l* being changed into the part *m* in the lower half of Fig. 7. The meeting 65 corners of the parts *f* *g* are soldered together and the said shelves are provided with tenons *p* which pass through slots *f'* in the backs *f* and are folded over to form hooks *q* which hold the back ends of said shelves firmly to 70 place.

All intermediate shelves are of the same construction as the end shelves, the only difference between them being that the intermediate shelves consist of two end shelves 75 placed back to back, thus facing in opposite directions, as shown in Fig. 1, and united by special elements as shown in Figs. 6 and 7. The openings at each end of the central part are closed by plates *d* and *e* which are pro-
80 vided with central holes *d'*. The plate *d* turns on the boss *a'* and carries the structure above it. The flanges *i* hold the cards *r* from falling out and the bar divides the assortment on the shelves. The hole in the 85 top plate *e* fits closely to the rod *b* and the nut *c* holds the two parts, stand and shelves, together. The latter revolving freely on said stem and, thereby, making all parts 90 easily and equally accessible. The flanged plates *f*, soldered at their meeting-edges, form a pillar from which radiate the shelves, and their flanges *g* hold the inside ends of the cards *r*.

What I claim is:

1. The combination with a base provided with a stem, of a sheet-metal pillar pro-
vided with slots, centrally pierced and square pieces mounted on the ends of said 100 pillar and on said stem and shelves having end-tenons in said slots.

2. The combination with a base provided with a stem, of a sheet-metal pillar pro-
vided with slots, centrally pierced and

square end-pieces on the ends of said pillar and on said stem, and shelves with tenons held in said slots, provided with U-shaped supports having bossed sides in the free end 5 of said shelves.

3. In a card-rack, a vertical frame, a plurality of horizontal supports rigidly secured to said frame, a vertical brace con-

necting the free ends of said supports, and bent lugs or extensions on said parts at the several points of contact to secure said parts together.

EDWARD C. DOUGLAS.
